SOLE COVER LASTING MACHINE

Anthony Cocozella, Jr., Albert J. Cocozella, and Clarence E. Cocozella, Lynn, Mass., assignors to United Shoe Machinery Corporation, Flemington, N. J., a corporation of New Jersey

Application November 23, 1945, Serial No. 630,188

16 Claims. (Cl. 12—1)

1

This invention consists in a new and improved machine for wrapping, or lasting, a flexible cover about the margin of a platform sole or insole.

The machine of our invention is particularly useful in the manufacture of shoes in which a flexible binding or cover strip is secured by one edge adjacent to the upper marginal face of a platform sole or an insole, then wrapped about the edge of the sole, usually also about the edge of the upper, and finally cemented to the lower or outer face of the sole. In this manner an ornamental sole edge effect is secured and the seam securing both the upper and the binding strip is enclosed and sealed. The binding or cover strip may be of ornamental textile material or it may be of leather or sheet plastic material and its upper edge may be attached to the sole piece or to the sock lining or in some cases to the margin of the upper. However the strip is attached, the wrapping operation, or cover lasting operation, as it is known in the trade, must be carried out so that the strip is wrapped tightly and smoothly about the margin of the sole and secured while under tension by cement to its outer face.

The principal object of the present invention is to provide an improved machine whereby this wrapping, or lasting, operation may be carried out continuously in the manner indicated and uniformly and at high speed. It will be understood that, if the binding or cover strip is not uniformly tensioned and secured, the fine continuous lines required in high-grade shoemaking are not realized and the sole is given a bulky and bulging appearance. The machine of our invention obviates these defects and produces work of the most highly satisfactory appearance. The operation of our machine is characterized by the continuous application to the binding strip of a rotary-overwiping-action supplemented in a rapid intermittent manner by a reciprocatory or rectilinear overwiping action. For example, we may use a tool having a helical configuration rotating continuously in contact with the free portion of the binding strip in such manner as to work it continuously over the edge of the sole piece and inwardly across its face, and impart to this tool an intermittent positive bodily movement inwardly across the face of the sole, thus subjecting the binding strip to a severe ironing and overwiping action. The tool is allowed to spin or screw itself outwardly after each inward movement without imparting any retrograde or outward wiping to the binding strip. Preferably and as herein shown the sole or shoe with the attached

2

binding is advanced by feeding means separate from the helical tool.

In some cases it is desired to employ a heat responsive cement and accordingly the machine of our invention is optionally characterized by the provision of means for heating of the binding strip or of a cemented zone in the binding strip before the strip is pressed into adhesive contact with the sole.

10 More particularly an important feature of our machine consists in a rotary tool having an operative helical surface, arranged to be driven at a predetermined speed and associated with cam means for intermittently reciprocating the tool simultaneously with its rotary movement. Preferably, and as herein shown, the shaft carrying the helical tool carries also a work feeding wheel which acts upon the sole adjacent to the area of the cover strip in process of being overwiped. As herein shown the feed wheel may be independently driven at a speed different from that of the helical wiping tool. Preferably, and as herein shown, the machine includes a swivel horn by which the sole of the shoe in process may be conveniently and positively supported in operative position with respect to the instrumentalities of the machine and a heated member which is arranged to engage the inner surface of the binding strip or cover. As additional features 15 20 25 30 35 means are provided for swinging the horn temporarily outwardly to facilitate presenting and releasing the work and also for temporarily displacing the helical tool and the heated member for the same purpose.

35 These and other features of the invention will be best understood and appreciated from the following description of a machine which constitutes one embodiment of our invention, selected for purposes of illustration and shown in the 40 accompanying drawings in which:

Fig. 1 is a view of the machine in side elevation.

Fig. 2 is a plan view of the machine.

Fig. 3 is a fragmentary view in section of the helical tool and associated parts.

45 Fig. 4 is a view in perspective on a larger scale showing a shoe in process by the machine, and

Fig. 5 is a view in elevation partly in section showing independent driving means for the tool and the feed wheel.

50 The illustrated machine comprises a base 10 carrying an upright overhanging frame 11 and a swivel jack. The jack comprises a plate 12 pivotally mounted between bracket members 13 on the base to swing about a horizontal axis and having a forwardly extending arm 14 for treadle

connections. A leaf spring 15 is mounted on a block 16 secured to the base 10 and bears upon the rear side of the jack plate 12, tending at all times to rock the jack inwardly. The pressure of the leaf spring may be adjusted by means of an adjusting screw 17 carried by a bracket 18 on the base and bearing upon the upper side of the spring. The operative position of the jack may be adjusted and set by a stop screw 19 carried by the plate 12 and bearing on the base. The jack plate 12 carries a cylindrical casing 20 having ball bearings in which is mounted a goose-neck horn 21 carrying a circular work plate 22 at its upper end. This plate rotates freely and is mounted in the vertical axis of the horn and is thus maintained in its sole-supporting position in all positions of the horn.

The upright frame 11 at its right hand end is formed with vertical guideways between which is mounted a bearing block 24. In this block is journaled a normally horizontal shaft 25 arranged to be driven by a pulley 26 fast to its outer end. The overhanging frame extends forwardly and is provided at its outer end with a second pair of vertical guideways between which is mounted a block 28 having bearings for the forward end of the shaft. The block 28 is formed with an upwardly extending hooked projection 29 upon which bears the forward end of a leaf spring 30 mounted in the upper portion of the machine frame. An adjusting screw 31 threaded into a plate in the frame serves to adjust the pressure of the spring upon the block.

The frame 11 has a lower branch 32 to which is secured a bracket having a downwardly and rearwardly extending arm 33 and a flat forwardly projecting portion 34. An adjustable abutment screw 35 in the bracket determines the operative position of the block 28 and the shaft journaled therein. At its forward end the bracket 33-34 extends in proximity to the work plate 22 of the horn and carries a pair of gauge rolls 36. These are unsymmetrically arranged with respect to the shaft, that is to say, the effective guiding line of the two rolls is inclined forwardly with respect to the axis of the shaft, and the first roll encountered by the work is located nearer to the shaft 25 than is the other roll.

The block 28 in which the shaft is journaled carries a stationary cam sleeve 37 having a single cam projection in its circumference. The shaft is shouldered at its outer end and carries a friction-tight feed roll 38 which is held upon the shaft between washers by a nut 39. Between the feed roll and the stationary cam sleeve 37 on the shaft is provided a longitudinally movable sleeve 40 having a pronounced helical thread formed on its surface. The sleeve is connected to the shaft by means of a longitudinal key 41 and is formed at its rear end with a single cam projection which cooperates with the cam projection of the stationary sleeve 37 in throwing the movable sleeve forwardly once in each revolution of the shaft. In practice we have found that a reciprocatory movement of $\frac{1}{8}$ to $\frac{1}{16}$ inch is satisfactory for the rectilinear overwiping movement of the helical tool.

A lifting lever 42 is pivotally mounted between ears on the machine frame and engages at its forward end with a link 43 connected to the hook-shaped projection of the block 28 carrying the forward end of the shaft 25. At its rear end the lever has treadle connections, and by depressing the rear end of the lever the forward end of the shaft is lifted against the pressure of

the spring 30 and separated temporarily from the work table of the horn to facilitate the introduction of work and its removal from the machine.

Secured to one side of the machine head is a forwardly inclined tubular guideway 44 in which is mounted a bar 45 curved inwardly and forwardly at its upper end to a position approximately above the sleeve 37. This bar 45 carries an upwardly extending casing 46 for an electric heating unit, and a downwardly extending spoon-shaped heater 47 arranged to run upon the inner surface of the binding strip, just before the strip comes into the range of the helical tool, for the purpose of heating and softening the cement carried by the binding strip. An angular lifting lever 48 pivotally mounted upon a stud 49 in the upper portion of the machine frame is connected through a slot in the guideway 44 to the heater bar 45 at its lower end and to the lifting lever 42 at its rear end. Accordingly, by depressing the treadle connection to the main lifting lever 42, the bar 45 carrying the heater is moved upwardly and forwardly thus retracting the heater from the work. The action of the leaf spring 30 in the top of the machine frame which is transmitted to the main lifting lever is also transmitted to the heater bar 45 to maintain it yieldingly at all times in its lower or operative position. The heater 47 is adjustably clamped in the upper end of the bar 45 and the operative position of the lower end of the heater is thus determined by this adjustment and by the abutment screw 35.

The machine is illustrated in Figs. 1-4 as having both the feed wheel 38 and the helical tool 40 driven by the shaft 25, and while this arrangement is entirely satisfactory, we have found it somewhat more advantageous to operate the feed roll at a higher speed than the helical tool. A preferred construction for this kind of operation is illustrated in Fig. 5 where, instead of a single solid shaft, we employ a hollow shaft 50 driven by a pulley 51, and a solid shaft 52 concentrically disposed therein and driven by a pulley 53. The solid shaft carries the feed roll 54 and the hollow shaft carries the helical tool 40 splined thereto by a key 41 as before explained. By using this arrangement, and driving the pulleys 51 and 53, respectively, from independent power sources, not shown, we are able to adjust and vary the speed ratio of the feed wheel to the helical tool in accordance with requirements of the work in hand.

In operation the horn 21 is swung outwardly by its treadle connections, the feed roll and associated parts are lifted through the lever 42, and the partially formed shoe with its edge-attached cover strip 61 is presented in working position. The sole 60 is rigidly supported by the freely rotatable work plate 22 of the horn and its edge guided for feeding movement by the gauge rolls 36. When the lever 42 is released, the feed roll bears upon the upper surface of the inverted sole with strong spring pressure. The tool 40 extends transversely across the edge of the sole and into contact with the outer surface of the unattached portion of the binding strip 61. The lower curved end of the heated member 47 extends into proximity to the inner surface of the cover strip so that as the shoe is advanced, the cement carried by the strip is warmed and rendered tacky.

As the machine is operated, the helical tool 40 subjects the cover strip to a continuous rotary overwiping action progressively in successive

areas of the strip as the shoe is advanced by the action of the feed roll 38. The rotary overwiping action is continuous and without interruption, and once in each revolution the tool 40 is bodily projected forwardly by cam action so that the area of the cover strip in contact with the tool is given a rectilinear overwiping. The two overwiping actions supplement each other and wrap the cover strip tightly and smoothly about the marginal edge of the sole 60 and press the tacky cement-coated margin of the strip firmly against the uppermost bottom surface of the sole so that it is fastened securely by cement in tensioned condition. It will be understood that the material of the cover strip is soft enough so that it conforms to or is grooved by the helical threads on the tool 40. Thus the rotary overwiping action is effective to draw the cover strip strongly into the desired position. The tool is advanced bodily and positively in approximately 10° of the shaft 20 rotation and is then released so that it is free to retract as it continues to rotate. This retracting movement is caused by the reaction of the helical thread against the work and occurs without any tendency to displace the cover strip from its overlasted position.

While the machine of our invention has been herein shown and described in connection with a cover wrapping, or lasting, operation performed off the last, it will be understood that should the shoe manufacturer prefer to carry out this operation with a last in the shoe, it is necessary only to remove the horn. Under these circumstances a lasted shoe may be presented to the gauge rolls 36 and supported by the hands of the operator while the sole is advanced by the said roll and guided in the proper predetermined path by the gauge rolls.

Having thus disclosed our invention and described in detail an illustrative embodiment thereof, we claim as new and desire to secure by Letters Patent:

1. A platform cover lasting machine comprising means for movably supporting a platform sole in inverted position, a helical tool disposed transversely across the marginal face of the supported sole, and mechanism for continuously rotating and intermittently reciprocating said tool while in contact with the platform cover.

2. A platform cover lasting machine comprising a rotatable and reciprocable wiping tool, and mechanism for continuously rotating and intermittently reciprocating said tool while in contact with the platform cover.

3. A machine for lasting the cover of a platform sole comprising a swivel horn for supporting the sole, a pair of edge gauge rolls for guiding the sole for movement upon the horn, a continuously rotating helical tool operating to draw the free margin of the cover over the upper face of the sole, means for intermittently reciprocating said tool while engaged with the cover, a heating device arranged to engage the inner surface of the cover in advance of the said tool, and spring means tending to hold the horn and tool in predetermined relation.

4. A machine for lasting platform covers, having in combination, means for guiding a platform sole with cover attached at one edge, a single tool for progressively working the free margin of the cover over the surface of the sole and pressing it into adhesive engagement therewith, said tool comprising a transversely disposed sleeve having a helical rib thereon, spring means for pressing

the sleeve toward the sole, and means for both rotating and reciprocating the sleeve.

5. A machine for lasting platform covers, having in combination, a sole gauge, a roll having a helical rib and being disposed transversely to the margin of a shoe in contact with said gauge, means for intermittently moving the roll inwardly to work the free portion of the cover over the sole, and means for continuously driving the roll with the same effect.

10 6. A machine for lasting platform covers, having in combination, a gauge for an inverted sole, a driven roll disposed transversely above the sole of the shoe positioned by the gauge and having a projecting helical rib, means for continuously rotating the roll in a direction to screw the free edge of the platform inwardly over the face of the sole, and a cam for intermittently throwing the roll inwardly without interrupting its rotation.

7. A machine for lasting sole covers, having in combination, means for supporting and guiding a sole with an edge-attached cover strip, a spring-pressed roll bearing against the sole and having a helical operating surface, means for driving the roll, and a cam shaped for positively advancing the roll in an axial direction to work the cover strip inwardly and then for releasing the roll whereby it may spin itself outwardly without disturbing the cover.

30 8. A machine for lasting sole covers, having in combination, means for supporting and guiding a sole with an edge-attached cover strip, a shaft extending transversely of the sole, a helical tool carried thereby in position to engage the cover strip, and a feed wheel carried thereby in position to engage the sole within its marginal edge and being rotatable about the axis of said helical tool.

9. A machine for lasting sole covers, having in combination, means for supporting and guiding a sole with an edge-attached cover, a shaft, a roll splined thereon and having a helical wiping surface, means for rotating the shaft with the said roll, and cam means for intermittently pushing the roll inwardly over the sole once in each revolution of the shaft.

40 10. A machine for lasting sole covers, having in combination, means for supporting and guiding in a horizontal path a sole with an edge-attached cover, a horizontal shaft carrying a rotary wiping tool and extending over the surface of the sole, a rocking journal for said shaft mounted to permit the shaft to swing toward and from the sole, spring means for pressing the shaft toward the sole, and an element for heating the cover movable simultaneously with the movement of the shaft.

11. A machine for lasting sole covers, having in combination, means for supporting and guiding in a horizontal path a sole with an edge-attached cover coated with heat-responsive cement, a rotary wiping tool acting on the cover to work it over the sole, and a retractable heated member mounted to engage the cover strip as it approaches the said wiping tool and acting to render tacky the cement coating of the strip.

12. A machine for lasting sole covers, comprising means for supporting and guiding in a horizontal path a sole carrying an edge-attached cover strip, a helical tool extending transversely across the face of the sole, means for rotating the tool to subject the cover strip to a continuous rotary overwiping, means for bodily projecting the tool once in each revolution thereof to subject the cover strip to rectilinear overwiping, and means

75 for feeding the sole.
